UNITED STATES PATENT OFFICE

STEPHEN ARNOLD MARPLES, OF LONDON, ENGLAND

ADVERTISING CLOCK

Application filed August 9, 1929, Serial No. 384,644, and in Great Britain August 10, 1928.

This invention relates to intermittently operated mechanism for exhibiting apparatus such as advertising or projection devices driven by spring, weight, electric or other power, and to time or speed controlling or controlled mechanism for indicating and recording devices and the like.

The present invention comprises intermittently operated motor driven advertising, indicating or recording apparatus, wherein the apparatus is driven by motor operated mechanism provided with intermittent releasing mechanism operatively connected to any suitable member of an adjacent clock, clock movement or other speed or time controlled mechanism. The relative direction of movement of both mechanisms is so arranged that any pressure exerted on or through the releasing mechanism upon a connecting member of the controlling mechanism will be in the direction of motion of such connecting member, so that there will be no retardation or braking action on the controlling mechanism.

The intermittently operated mechanism may be driven by its motor through toothed gearing of which any one or more shaft or shafts of the intermittently released mechanism has a crank and a connecting rod extending from the crank pin to a notched or toothed wheel fixed on a suitable shaft of the clock train or other speed or time controlled mechanism, the notched wheel being driven at a slower peripheral speed than the crank pin, the free end of the connecting rod being provided with a transverse pin or member adapted to be engaged by the teeth or the like of the notched wheel and hold or delay the crank until the notched wheel has moved sufficiently to allow the crank to turn over its dead centre and enable the motor to rotate the crank so that it will perform the return movement or a series of such movements of the connecting rod necessary to carry its transverse pin into a position in which it will be engaged by an adjacent tooth of the notched wheel, and the operation is repeated. The connecting rod is preferably made slightly extensible and compressible and restorable

by spring action when the extending or compressing force is removed.

The motor driven advertising, indicating or recording devices may be mounted on discs or drums arranged on vertical or horizontal axes, a convenient method being to support them on a disc mounted on a vertical axis running in jewel or other suitable frictionless or practically frictionless bearings or pivot centres, and the devices may be supported by gravity or otherwise in recesses or guides provided in the face of the disc at uniform distances apart circumferentially. The devices may be transparencies for use in illuminated or projection apparatus.

The movement of the toothed wheel may be controlled by clock escapement mechanism and the clock train provided with an ordinary clock face provided with hour or minute hands.

A manner of carrying out the invention is illustrated by the accompanying drawings wherein Figure 1 is a front elevation of a clock case containing the device, Figure 2 a section side elevation showing diagrammatically the main elements of the apparatus, Figure 3 a diagram of the intermittently operated mechanism, when using two motors, Figure 3a is a diagram of the intermittent mechanism when using one motor only, Figure 4 a plan of the same, Figures 5 and 6 alternative details of holders for the transparencies or slides, and Figure 7 is a detail of the train mechanism.

In these drawings 2 is a casing containing a translucent clock dial 3 and a screen 8 which may be a sheet of frosted glass, a is a disc on which transparent devices 6 or slides containing the matter to be exhibited are arranged, 4 a lamp arranged above the transparencies 6 and also behind the translucent clock dial 3. The rays from the lamp 4 pass through a condenser lens 5 arranged above the transparencies 6, that is at a position under which each of the transparencies 6 will be moved intermittently so that the projected rays will pass downwards on to a reflector 7 inclined in such a manner as to reflect the projected rays on to the screen 8.

The disc a carrying the transparencies 6

is rotated by a shaft 9 mounted at each end in adjustable pivot bearings 10 and 11 and carrying a toothed mitre or bevel wheel 12 arranged to mesh with a toothed pinion 13 mounted on a shaft 14 carrying a pinion 15 and a crank 16.

In order to allow for the taking up of play between the parts, the toothed pinion 13 is not fixed directly to the shaft 14 but connected thereto by means of a spring 13a of which one end is fastened to the wheel 13 and the other to a collar 13 fixed on the shaft 14 and through which power is transmitted. Such means for taking up the play may, however, be arranged at any other suitable portion of the gearing.

The disc *a* carrying the transparencies 6 when arrested at each periodic movement is retained by a pawl 45 pivoted to a supporting member 49, the free end of the pawl being arranged to engage with a notch or groove 46 provided in the face of the disc *a*, the number of notches provided in the disc *a* corresponding to the number of transparencies 6. The pinion 15 forms the last wheel of a train of toothed gears 17, 18, 19, 20, 21, 23 of which 23 is driven by a spring 24 in a manner similar to a clock, thereby comprising a motor driving the disc *a* containing the transparencies 6 or slides containing the matter to be exhibited and also driving a crank 16 which is connected by a connecting rod 25 to releasing mechanism comprising a second train of wheels. Any suitable governor such as an air vane or a fly wheel 9a may be provided on this first mentioned train of wheels.

The second train of wheels in the example shown is driven by a spring 27 in a manner similar to the first train described above. The spring 27 drives through a train of toothed gears 28, 29, 30, 31, 32 and 33, a notched or toothed wheel 34, and on the shaft 35 carrying the toothed wheel 34 is also a toothed wheel 36 gearing with a pinion 37 on a shaft 38 carrying an escapement wheel 39 with which co-operates an escapement 40 controlled by a pendulum 41 in the usual manner. The toothed wheel 30 of the time controlled train, gears with a wheel 44 driving the train of the hands 3a, 3b of the clock dial 3.

The two trains of wheels are carried in bearings in front and rear plates 42 and 43 as in ordinary clock work actions.

The driving powers of the two springs 24 and 27 are approximately of equal strength, and the trains are so designed that the notched or toothed wheel 34 makes one revolution in about the same time that the crank 16 makes twenty revolutions, and the wheel 34 contains nine notches in its periphery. The crank 16 and the notched or ratchet wheel 34 form interconnecting transmission members connected together by the connecting rod 25.

The shaft 14 carrying the crank 16 is approximately at the same level as the shaft of the notched wheel 34, and the connecting rod 25 extends to the wheel 34 and has at its free end a forked portion carrying a transverse member or pin 35 which engages the notches on the upper portion of the notched wheel 34.

The function of the connecting rod 25 is to arrest or delay the motion of the crank 16 at or during a predetermined period corresponding to the desired period of projection of the transparencies 6 and corresponding to the timing by the clock train. To effect this function of the crank 16 and notched wheel 34 are arranged to rotate in the same direction, and the crank 16 arranged to impart a pull on the connecting rod 25 during the half revolution when the crank 16 is uppermost, that is to say above the shaft 14, and its direction of motion is away from the notched wheel 34 of which the upper notches are turning slowly towards the crank 16. The pin 35 of the connecting rod 25 is held by one of the notches in the wheel 34 while approaching the crank 16 and until the crank 16 reaches the position furthest from the notched wheel 34, whereupon the crank 16 continues to turn without any restraint downwards and backwards beneath its shaft 14 by the action of the spring 24, and the connecting rod 25 is similarly driven back until the connecting rod pin 35 is immediately disengaged from the notch in the wheel 34 and slips back into the next notch at or before the instant when the crank has completed the half turn below its shaft. The crank 16 then continues to turn above its shaft until its rotation is arrested or delayed by the pin 35 dropping by gravity and engaging the bottom of the notch it has just entered, when the action is repeated.

In order to provide a movement of the disc or slide holder equivalent to one complete revolution of the crank 16 the teeth of the mitre wheels 12 and 13 operating the slide holder *a* may be constructed with free play for instance between the faces of the teeth of the wheels 12 and 13, so as to allow the slide holder to continue to revolve by its own momentum after each periodic arrest of the driving mechanism until such play is taken up and the slide holder *a* is engaged and held by the pawl 45 dropping into the groove 46 as described. Upon the motion of the disc holder *a* being arrested by the taking up of the play between the parts, or by the action of an interposed spring it may be held by a suitable ratchet device from any tendency to recoil.

The throw of the crank 16 is arranged to be greater than the distance between the bottoms of consecutive notches in the wheel 34 for the purpose of ensuring the free move-

ment of the pin 35 from one notch to the next and to allow the crank 16 to run well forward towards the extremity of its travel before it is arrested or delayed by the engagement of the pin 35 in the next notch of the wheel 34 as described.

In order to allow of an increase in the forward movement of the connecting rod 25 and also to protect the train of the notched wheel 34 from shock the connecting rod 25 may be made of a light strip of metal or other suitable material and bent or waved as at 25a or otherwise made extensible and contractable, and thereby allow of an extension in its length when arrested by the notches in the wheel 34 and so accommodate pull or momentum of the train driving it.

In a modification of the apparatus the spring 27 and toothed wheels 28 and 29 are dispensed with and the wheel 30 driven from the wheel 22 by means of intermediate wheels 47 and 47c of equal size shown in Figure 3 in dotted lines. In this modification the wheel 47 is free on the shaft 47a and is connected to the wheel 47c by a power maintaining spring 47b as shown in Figure 7. The shaft 47a is driven by the fixed wheel 47c from the wheel 22 and transmits the power through the spring 47b and the wheel 47 to the wheel 30 of the clock train. The intermediate wheels 47 and 47c may be substituted by any other suitable transmission mechanism.

The transparencies 6 are held by gravity in angle pieces 48 arranged to form corner pieces extending from the disc a at equal distances from openings a2 provided for the projection rays. Instead of the angle pieces 48 the transparencies may be arranged to fit in slides 50 (see Figure 6) fastened over the openings a2 by screws or rivets passing through the holes 51, the openings a2 being made rectangular to correspond to the rectangular opening 53 provided in the slides 50. Figure 5 illustrates a slide for holding charts or other devices for use with apparatus not constructed for projecting transparencies.

The motor operated mechanism may be arranged to drive switching devices for electrical circuits, or relay mechanism.

The power expended by the crank driving train may be employed to impart impulses, or control impulses given, to any desired mechanism for any desired purposes, by direct mechanical action or interposition of parts, electric contacts and similar means.

A device of this character is illustrated by Figure 4 wherein the disc a is of metal and is provided with a number of circumferentially spaced blocks a3 on which bears an electric contact brush a4, the brush a4 being connected to one lead a5 of an electric supply circuit, while the other lead a6 of the electric supply circuit is connected to the disc a through the shaft 9.

Further the delay or arrest of the crank 16 may be effected upon its passage beneath its shaft instead of above it as shown in Figure 3, and the pin 35 at the forked end of the connecting rod 25 in such case may press **70** against the notches on the under portion of the notched wheel 34, which are moving away from the crank 16.

What I claim and desire to secure by Letters Patent is:—

1. Intermittently operated mechanism, comprising motor operated mechanism, an interconnecting transmission member therefor, motor operated speed controlling mechanism, an interconnecting transmission member **80** therefor, an intermittently rotated member, means for driving the same from the motor operated mechanism, and a connecting member, the connecting member being at one end continuously connected to the interconnecting transmission member of the motor operated mechanism and at the other end intermittently connected to the interconnecting transmission member of the speed controlling mechanism, the relative directions **85** of movement of both interconnecting transmission members being such that any pressure exerted by the motor operated mechanism through the connecting member will be in the operative direction of motion of the **90** interconnecting transmission member of the speed controlling mechanism.

2. Intermittently operated mechanism, comprising motor operated mechanism, motor operated speed controlling mechanism, **100** a ratchet wheel, a crank, a connecting member, an intermittently rotated member and means for driving the same from the motor operated mechanism, the crank being driven by the motor operated mechanism, while the ratchet wheel is driven by the motor operated speed controlling mechanism, the connecting member being connected at one end to the crank and formed at the other as a pawl **105** engaging the teeth of the ratchet wheel, the motor operated mechanism and the speed controlling mechanism being driven relatively to one another in such directions that any pressure exerted by the pawl thereof on the ratchet teeth will be in the operative direction of motion of the connecting member so that there will be no retarding or braking action on the controlling mechanism. **110**

3. Intermittently operated mechanism, comprising a train of toothed wheels, a motor for operating the same, a speed controlling train of toothed wheels, a motor for operating the same, a ratchet wheel, a crank, a connecting member, an intermittently rotated disc, toothed gearing for rotating the disc, means for driving the toothed gearing of the disc from the first train of spur wheels, the crank being driven by the motor operated mechanism, while the ratchet wheel is driven by the motor operated speed control mecha- **120** **125** **130**

nism, the connecting member being connected at one end to the crank and formed at the other as a pawl engaging the teeth of the ratchet wheel and the motor operated mechanism and the speed controlling mechanism being driven relatively to one another in such directions that any pressure exerted by the pawl thereof on the ratchet teeth will be in the operative direction of motion of the connecting member so that there will be no retarding or braking action on the controlling mechanism.

4. Intermittently operated mechanism, comprising a train of toothed wheels, a motor for operating the same, a speed controlling train of toothed wheels, a motor for operating the same, a ratchet wheel, a crank, a connecting member, an intermittently rotated disc having a number of circumferentially spaced openings, means for holding over the openings, slides containing the matter to be exhibited, toothed gearing for rotating the disc, means for driving the toothed gearings of the disc from the first train of toothed wheels, the crank being driven by the motor operated mechanism, while the ratchet wheel is driven by the motor operated speed control mechanism, the connecting member being connected at one end to the crank and formed at the other as a pawl engaging the teeth of the ratchet wheel, the motor operated mechanism and the speed controlling mechanism being driven relatively to one another in such directions that any pressure exerted by the pawl thereof on the ratchet teeth will be in the operative direction of motion of the connecting member so that there will be no retarding or braking action on the controlling mechanism.

5. Periodically controlled mechanism, comprising a train of toothed wheels, a motor for operating the same, a speed controlling train of toothed wheels, a motor for operating the same, a ratchet wheel, a crank shaft, a connecting rod, an intermittently rotated disc rotating on a vertical axis, mitre gearing, the disc being rotated by the mitre gearing and the mitre gearing from the first train of toothed wheels, the crank being driven by the motor operated mechanism, while the ratchet wheel is driven by the motor operated speed control mechanism, the connecting member being connected at one end to the crank and formed at the other as a pawl engaging the teeth of the ratchet wheel, the motor operated mechanism and the speed controlling mechanism being driven relatively to one another in such directions that any pressure exerted by the pawl thereof on the ratchet teeth will be in the operative direction of motion of the connecting member so that there will be no retarding or braking action on the controlling mechanism.

6. Intermittently operated mechanism, comprising a train of toothed wheels, a motor

for operating the same, a speed controlling train of toothed wheels, a motor for operating the same, a ratchet wheel, a crank, a connecting member, an intermittently rotated metal disc having a number of circumferentially spaced insulating blocks, a metal brush arranged to bear on the blocks and disc alternately during the rotation of the disc, an intermittently broken and closed electric circuit of which one end is connected to the disc and the other to the brush so that the circuit will be intermittently made and broken during the rotating of the disc, toothed gearing for rotating the disc, means for driving the toothed gearing of the disc from the first train of spur wheels, the crank being driven by the motor operated mechanism, while the ratchet wheel is driven by the motor operated speed control mechanism, the connecting member being connected at one end to the crank and formed at the other as a pawl engaging the teeth of the ratchet wheel, the motor operated mechanism and the speed controlling mechanism being driven relatively to one another in such directions that any pressure exerted by the pawl thereof on the ratchet teeth will be in the operative direction of motion of the connecting member so that there will be no retarding or braking action on the controlling mechanism.

7. Intermittently operated mechanism, comprising a train of toothed wheels, a motor for operating the same, a speed controlling train of toothed wheels, a motor for operating the same, a ratchet wheel, a crank, a connecting member, an intermittently rotated disc, means for preventing the return of the disc after each intermittent movement, toothed gearing for rotating the disc, means for driving the toothed gearing of the disc from the first train of toothed wheels, the crank being driven by the motor operated mechanism, while the ratchet wheel is driven by the motor operated speed control mechanism, the connecting member being connected at one end to the crank and formed at the other as a pawl engaging the teeth of the ratchet wheel, the motor operated mechanism and the speed controlling mechanism being driven relatively to one another in such directions that any pressure exerted by the pawl thereof on the ratchet teeth will be in the operative direction of motion of the connecting member so that there will be no retarding or braking action on the controlling mechanism.

8. Intermittently operated mechanism, comprising a train of toothed wheels, a motor for operating the same, a speed controlling train of toothed wheels, a motor for operating the same, a ratchet wheel, a crank, a connecting member, an intermittently rotated disc, rotating on a vertical axis, a series of radially arranged grooves on the upper face of the disc, a pivoted pawl of which the lower end

- rests on the disc in the path of the radial grooves so as to engage one of such grooves after each intermittent movement of the disc, toothed gearing for rotating the disc, means for driving the toothed gearing of the disc from the first train of toothed wheels, the crank being driven by the motor operated mechanism, while the ratchet wheel is driven by the motor operated speed control mechanism, the connecting member being connected at one end to the crank and formed at the other as a pawl engaging the teeth of the ratchet wheel, the motor operated mechanism and the speed controlling mechanism being driven relatively to one another in such directions that any pressure exerted by the pawl thereon on the ratchet teeth will be in the operative direction of motion of the connecting member so that there will be no retarding or braking action on the controlling mechanism. 70
10. Periodically controlled mechanism, comprising a train of toothed wheels, a motor for operating the same, a speed controlling train of toothed wheels, a motor for operating the same, a ratchet wheel, a crank shaft, a connecting rod, an intermittently rotated disc rotating on a vertical axis, means for taking up the play of the parts, a mitre gearing, the disc being rotated by the mitre gearing and the mitre gearing rotated through the means for taking up the play of the parts from the first train of toothed wheels, the crank being driven by the motor operated mechanism, while the ratchet wheel is driven by the motor operated speed control mechanism, the connecting member being connected at one end to the crank and formed at the other as a pawl engaging the teeth of the ratchet wheel, the motor operated mechanism and the speed controlling mechanism being driven relatively to one another in such directions that any pressure exerted by the pawl thereon on the ratchet teeth will be in the operative direction of motion of the connecting member so that there will be no retarding or braking action on the controlling mechanism. 75
15. Intermittently operated mechanism, comprising motor operated mechanism, motor operated speed controlling mechanism, a ratchet wheel, a pawl operatively connected to the ratchet wheel, a crank, a connecting member, an intermittently rotative member and means for driving the same from the motor operated mechanism, the ratchet wheel being driven by the speed controlling mechanism while the crank is driven by the motor operated mechanism and the connecting member is connected at one end to the crank, while its other end is linked to the pawl of the ratchet wheel, and the length of the connecting member is such that when the engaged tooth of the ratchet wheel moves to disengaging position the crank is free to move over its dead centre and so allow intermittent motion of the intermittently rotative member to be effected. 80
20. Intermittently operated mechanism, comprising motor operated mechanism, an interconnecting transmission member therefor, motor operated speed controlling mechanism, an interconnecting transmission member therefor, an intermittently rotated member, means for driving the same from the motor operated mechanism, and a connecting member, the connecting member being extensible and contractible, the connecting member being at one end continuously connected to the interconnecting transmission member of the motor operated mechanism and at the other end intermittently connected to the interconnecting transmission member of the speed controlling mechanism, the relative directions of movement of both interconnecting transmission members being such that any pressure exerted by the motor operated mechanism through the connecting member will be in the operative direction of motion of the interconnecting transmission member of the speed controlling mechanism. 85
25. Intermittently operated mechanism, comprising motor operated mechanism, an interconnecting transmission member therefor, motor operated speed controlling mechanism, a ratchet wheel, a crank, a connecting member, an intermittently rotated member and means for driving the same from the motor operated mechanism, the ratchet wheel being driven by the speed controlling mechanism while the crank is driven by the motor operated mechanism and the connecting member is connected at one end to the crank, while its other end is linked to the pawl of the ratchet wheel, and the length of the connecting member is such that when the engaged tooth of the ratchet wheel moves to disengaging position the crank is free to move over its dead centre and so allow intermittent motion of the intermittently rotative member to be effected. 90
30. Intermittently operated mechanism, comprising motor operated mechanism, an interconnecting transmission member therefor, motor operated speed controlling mechanism, a ratchet wheel, a crank, a connecting member, an intermittently rotated member and means for driving the same from the motor operated mechanism, the ratchet wheel being driven by the speed controlling mechanism while the crank is driven by the motor operated mechanism and the connecting member is connected at one end to the crank, while its other end is linked to the pawl of the ratchet wheel, and the length of the connecting member is such that when the engaged tooth of the ratchet wheel moves to disengaging position the crank is free to move over its dead centre and so allow intermittent motion of the intermittently rotative member to be effected. 95
35. Intermittently operated mechanism, comprising motor operated mechanism, an interconnecting transmission member therefor, motor operated speed controlling mechanism, a ratchet wheel, a crank, a connecting member, an intermittently rotated member and means for driving the same from the motor operated mechanism, the ratchet wheel being driven by the speed controlling mechanism while the crank is driven by the motor operated mechanism and the connecting member is connected at one end to the crank, while its other end is linked to the pawl of the ratchet wheel, and the length of the connecting member is such that when the engaged tooth of the ratchet wheel moves to disengaging position the crank is free to move over its dead centre and so allow intermittent motion of the intermittently rotative member to be effected. 100
40. Intermittently operated mechanism, comprising motor operated mechanism, an interconnecting transmission member therefor, motor operated speed controlling mechanism, a ratchet wheel, a crank, a connecting member, an intermittently rotated member and means for driving the same from the motor operated mechanism, the ratchet wheel being driven by the speed controlling mechanism while the crank is driven by the motor operated mechanism and the connecting member is connected at one end to the crank, while its other end is linked to the pawl of the ratchet wheel, and the length of the connecting member is such that when the engaged tooth of the ratchet wheel moves to disengaging position the crank is free to move over its dead centre and so allow intermittent motion of the intermittently rotative member to be effected. 105
45. Intermittently operated mechanism, comprising motor operated mechanism, an interconnecting transmission member therefor, motor operated speed controlling mechanism, a ratchet wheel, a crank, a connecting member, an intermittently rotated member and means for driving the same from the motor operated mechanism, the ratchet wheel being driven by the speed controlling mechanism while the crank is driven by the motor operated mechanism and the connecting member is connected at one end to the crank, while its other end is linked to the pawl of the ratchet wheel, and the length of the connecting member is such that when the engaged tooth of the ratchet wheel moves to disengaging position the crank is free to move over its dead centre and so allow intermittent motion of the intermittently rotative member to be effected. 110
50. Periodically controlled mechanism, comprising a train of toothed wheels, a motor for operating the same, a speed controlling train of toothed wheels, a motor for operating the same, a ratchet wheel, a crank shaft, a connecting rod, an intermittently rotated disc rotating on a vertical axis, a spring surrounding the crank shaft, and two intermeshing mitre wheels, one of the mitre wheels being fixed to the rotated disc while the other runs loose on the crank shaft, the spring being fixed at one end to the loose mitre wheel and at the other to the crank shaft, the disc being rotated by the mitre wheel fixed thereon and the other mitre wheel in gear therewith by the spring from the crank shaft, the crank being driven by the motor operated mechanism. 115
55. Intermittently operated mechanism, comprising motor operated mechanism, motor operated speed controlling mechanism, a ratchet wheel, a crank, a connecting member, an intermittently rotated member and means for driving the same from the motor operated mechanism, the crank being driven by the motor operated mechanism, while the ratchet wheel is driven by the motor operated mechanism. 120
60. Intermittently operated mechanism, comprising motor operated mechanism, motor operated speed controlling mechanism, a ratchet wheel, a crank, a connecting member, an intermittently rotated member and means for driving the same from the motor operated mechanism, the crank being driven by the motor operated mechanism, while the ratchet wheel is driven by the motor operated mechanism. 125
65. Intermittently operated mechanism, comprising motor operated mechanism, motor operated speed controlling mechanism, a ratchet wheel, a crank, a connecting member, an intermittently rotated member and means for driving the same from the motor operated mechanism, the crank being driven by the motor operated mechanism, while the ratchet wheel is driven by the motor operated mechanism. 130

speed controlling mechanism, the connecting member being extensible and contractible and connected at one end to the crank and formed at the other as a pawl engaging the teeth of the ratchet wheel, the motor operated mechanism and the speed controlling mechanism being driven relatively to one another in such directions that any pressure exerted by the pawl thereon on the ratchet teeth will be in the operative direction of motion of the connecting member so that there will be no retarding or braking action on the controlling mechanism.

14. Intermittently operated mechanism, comprising motor operated mechanism, motor operated speed controlling mechanism, a ratchet wheel, a pawl operatively connected to the ratchet wheel, a crank, a connecting member, an intermittently rotative member and means for driving the same from the motor operated mechanism, the ratchet wheel being driven by the speed controlling mechanism while the crank is driven by the motor operated mechanism and the connecting member is connected at one end to the crank, while its other end is linked to the pawl of the ratchet wheel, and the connecting member being extensible and contractible and its length such that when the engaged tooth of the ratchet wheel moves to disengaging position the crank is free to move over its dead centre and so allow intermittent motion of the intermittently rotative member to be effected.
15. Intermittently operated mechanism, comprising a train of toothed wheels, a motor for operating the same, a speed controlling train of toothed wheels, a motor for operating the same, a ratchet wheel, a crank, a connecting member, an intermittently rotated disc rotating on a vertical axis, toothed gearing for rotating the disc, means for driving the toothed gearing of the disc from the first train of spur wheels, the crank being driven by the motor operated mechanism, while the ratchet wheel is driven by the motor operated speed control mechanism, the connecting member being connected at one end to the crank and formed at the other as a pawl engaging the teeth of the ratchet wheel, the motor operated mechanism and the speed controlling mechanism being driven relatively to one another in such directions that any pressure exerted by the pawl thereon on the ratchet teeth will be in the operative direction of motion of the connecting member so that there will be no retarding or braking action on the controlling mechanism.

In witness whereof I affix my signature.
STEPHEN ARNOLD MARPLES.
